ATTORNEY

UNITED STATES PATENT OFFICE.

WILLIAM S. SHARPNECK, OF DENVER, COLORADO

ROCK BREAKER AND PULVERIZER.

SPECIFICATION forming part of Letters Patent No. 315,670, dated April 14, 1885.

Application filed June 11, 1884. (No model.)

To all whom it may concern:

Be it known that I, WILLIAM S. SHARPNECK, a citizen of the United States of America, residing at Denver, in the county of Arapahoe 5 and State of Colorado, have invented certain new and useful Improvements in Rock Breakers and Pulverizers, of which the following is a specification, reference being had therein to the accompanying drawing.

10 My invention has reference to machines for pulverizing or reducing rock, &c.; and it consists in the improved construction whereby the material to be treated is effectively and quickly reduced, and the general construction of the 15 machine improved and simplified, as hereinafter more particularly described and claimed.

The accompanying drawing, forming a part 20 of this specification, shows a central vertical section of a machine in accordance with my invention.

A indicates a mortar provided at its upper edge with an outwardly-projecting flange, *a*, and tapering toward its lower end, where it is connected integrally to and supported by a 25 base, B, having an opening, *b*, forming an exit-passage from the interior of the mortar A through the base B. The opening *b* is arranged to form an annular seat, *c*, at the bottom of the mortar A, upon which bears the lower 30 edge of a tapering cylinder, C, concentric with and resting snugly in the mortar A, as shown in the drawing, and it may be of chilled or ordinary cast-iron, as preferred. The upper edge of the cylinder C is preferably flush with 35 the top of the mortar. Above the mortar is a cap, D, cast with an outwardly-projecting flange, *d*, at its bottom, which flange is perforated to receive bolts *e*, which pass through the flange *a* of the mortar A, and are provided 40 with nuts *f*, to secure said cap in position.

The central portion of the cap is extended vertically to form a throat, E, and a band or ring, F, extends vertically and integrally from the cap, forming, in connection with the central 45 portion or throat, E, an annular hopper, G, which communicates with the interior of the mortar A through an opening, *g*, formed in the central portion of the cap D.

I have shown but one opening; but it is evident that more may be used, if preferred, and an additional opening is shown in dotted lines on the opposite side of the cap. The

throat E is interiorly cut away, and may be threaded to receive the lower portion of the vertical cylinder H, which may be of wrought 55 or cast metal, as preferred, the lower edge of which bears upon a shoulder, *h*, formed by the cut-away portion of the throat. The upper end of the cylinder H has secured thereon and supports a head-casting, I, which is 60 provided with a depending flange, *i*, which embraces the outer side of the said cylinder, and may be screwed thereon or secured in any other manner. An interior annular rib or flange, *j*, in said head-casting I forms a bearing for the depending hub J of a drive-pulley, K, having a vertical recess formed eccentrically in said hub, which is adapted to snugly receive a bearing-box composed of two sections, *k l*, which are secured together by bolts 70 *m* and nuts *n*, and are recessed to conjointly receive and retain the ball L on the top of a vertical pestle-bar, M, suspended over the discharge opening *b*, so that the lower extremity of said bar is located near the lower edge of 75 the tapering cylinder C. The lower portion of the bar M is tapered, but more moderately than the mortar A and cylinder C, and the said tapered portion of the bar M is incased by a removable sleeve, N, which is preferably 80 of chilled metal to render it hard and durable, and contacts with the interior side of the cylinder C. This sleeve N is supported in position by means of a disk, *o*, secured to the lower end face of the bar M by a screw, *p*. The 85 web O of the drive-pulley K is perforated to permit the passage of a stud-bolt, P, the lower end of which is secured in the upper section, *k*, of the bearing-box. A nut and jam-nut, *q*, engaging the upper threaded end of the bolt, 90 is adapted to move the bolt P to vertically adjust the bearing-box and the pestle-bar M. The lower section, *l*, of the bearing-box is cut away at *r*, to permit a limited play of the pestle-bar M therein, and the consequent 95 movement of the spherical end L of said bar in its bearing box.

The operation of the machine is as follows: The material to be treated having been fed into the mortar from the hopper G through 100 the opening *g* of the same, it occupies a position between the interior face of the cylinder C and the exterior of the sleeve N. The pulley K, being driven from any suitable source

of power, rotates the hub J, and, by reason of the eccentric position of the bearing-box therein and of the ball-and-socket joint formed by the ball L in said bearing-box, a revolving motion is imparted to the upper part of the pestle M, so that its extreme lower end will have but little motion, while at a point distant from the bottom its motion will be increased, so as to have a kind of wobbling motion in the cylinder C, thereby crushing the material first against the upper part of the said cylinder, and then as the material becomes finer it falls down, and is then acted on again and again until it becomes fine enough to pass between the small annular space between the lower end of the pestle and mortar, where it receives a grinding action that will reduce the material to an impalpable powder, if desired, as the degree of fineness to which the material is reduced can be perfectly regulated by elevating or lowering the pestle M in the mortar by adjusting the nuts on the bolt P. It will be seen that the lower end of the pestle, is freely and loosely suspended in the mortar, so that it will easily adapt itself to the amount of material in the bottom of the mortar, as the bolt P will allow it to rise, as indicated in dotted lines. Furthermore, should any small object harder than the machine be intended to crush get between the mortar and pestle, the latter will yield sufficiently to allow the object to pass through without detriment to the machine. This loose suspension has the further advantage that as there are no bearings below the mortar or pestle there is no probability of any of the material getting into the bearings. It will also be seen that the extreme lower end of the pestle is semi-globular, which gives a better grinding-surface when the material has reached almost its finest state.

It will be obvious that the structure as illustrated and described is of comparatively inexpensive construction, inasmuch as all the sub-parts thereof may be readily produced by casting. Furthermore, such a machine will prove most effective in operation, as the parts do not involve delicate adjustment, and hence are not liable to become easily deranged or broken.

In some cases I place rollers between the hub J and the casting I to relieve the friction, and for the same purpose I may place rollers or balls between the web of the pulley and the top of said casting I, as shown in dotted lines.

I do not wish to limit myself to the exact construction here shown, as it is evident that it may be varied without departing from the spirit of my invention.

I am aware that a paint-mill has been provided with a conical grinding-surface suspended in fixed bearings so as to have a steady concentric rotary motion; but such conical grinding-surface was not loosely suspended, as it was guided by a double bearing above.

I am also aware that ball-and-socket joints

have been used to suspend eccentric-moving grinding-surfaces, and hence do not claim either of these constructions, broadly.

70

What I claim as new is—

1. The combination, in a breaking and pulverizing machine, of a mortar, a pestle having its lower end loosely suspended therein, means, substantially as described, for giving motion to the pestle, and a ball-and-socket joint constructed to perform the double function of suspending the pestle and communicating motion to the same, substantially as described.

80

2. The combination, in a breaking and pulverizing machine, of a mortar, a pestle having its lower end loosely suspended therein, a driving-wheel, an eccentric connected with said driving-wheel, and a ball-and-socket joint carried by said eccentric and constructed to perform the double function of supporting the pestle and communicating motion to the same, substantially as described.

85

3. The combination, in a breaking and pulverizing machine, of a mortar, a pestle having its lower end loosely suspended therein, a driving-wheel, an eccentric connected with said driving-wheel, a ball-and-socket joint located in said eccentric, and means for raising and lowering said ball and socket in said eccentric, substantially as described.

90

4. The combination, in a machine for breaking or pulverizing rock or similar material, of a mortar contracted toward its lower end, provided interiorly with a cylinder, C, and having a discharge-opening, a pestle having a tapered portion extending into said mortar and working therein, and a removable shoe or sleeve embracing said tapered portion, having its lower portion of semi-globular form, and secured to the tapered end of said pestle, substantially as described.

100

5. The combination, in a machine for breaking or pulverizing rock or similar material, of a mortar having a suitable discharge, a cap bolted to said mortar and provided with the throat E, an outer vertical band or ring forming a hopper, and a supply-opening, g, a pestle extending through said throat into said mortar, and devices above the cap for operating said pestle, substantially as set forth.

110

6. The combination, in a machine for breaking or pulverizing rock or similar material, of a mortar having a suitable discharge, a cap bolted to said mortar and forming a supply-hopper therefor, a cylinder, H, a head-casting secured to said cylinder H, the driving devices, a pestle extending through the cylinder and cap into the mortar, the upper end of said pestle being spherically enlarged to bear universally, and a bearing-box eccentrically located in the driving devices, substantially as set forth.

120

7. The combination, in a machine for breaking or pulverizing rock or similar material, arranged and constructed substantially as described, of a head-casting supported as set forth, and provided with an interior rib, j, a

130

drive-pulley, K, having a hub extending into the head-casting and bearing on the rib of the same, a box located eccentrically in the hub, and a pestle bearing in said box, and a mortar forming a support for the whole, substantially as and for the purpose specified.

In testimony whereof I affix my signature, in

presence of two witnesses, this 3d day of June, 1884.

WILLIAM S. SHARPNECK.
